BUCKLE

Douglas J. Harvey, Nutley, N. J.

Application February 21, 1934, Serial No. 712,279

2 Claims. (Cl. 24—163)

This invention relates, generally, to buckles, and the invention has reference, more particularly, to a novel improved buckle of the stud type, i. e. the type of buckle having a stud for engaging sockets provided in the strap, belt or other means engageable by the buckle.

Belts, straps and the like, having buckles of the stud type as heretofore generally constructed, have been difficult to adjust as to length owing to the inherent difficulty of sliding or moving the belt or strap through the buckle. This difficulty has been due to the buckle construction, the same ordinarily having fixed retaining means for holding the belt in engagement with the buckle stud so that it is very difficult and decidedly inconvenient to disengage the belt from the stud, with the result that these buckles have never become very popular.

The principal object of the present invention is to provide a novel buckle of the stud type having means for enabling the ready disengagement of the belt or strap served thereby from the buckle stud, whereby the adjustment of the belt or strap with respect to the buckle is rendered easy.

Another object of the present invention lies in the provision of a novel buckle of the above character that is of simple, rugged construction and is attractive in appearance.

Other objects of this invention, not at this time more particularly enumerated, will be clearly understood from the following detailed description of the same.

The invention is clearly illustrated in the accompanying drawing, in which:—

Fig. 1 is a fragmentary view in front elevation of a strap or belt equipped with the novel buckle of this invention.

Fig. 2 is a top plan view of the structure shown in Fig. 1.

Fig. 3 is a transverse central sectional view of the structure shown in Fig. 2.

Fig. 4 is a fragmentary top plan view of the belt and buckle and illustrates the manner of adjusting the belt with respect to the buckle.

Fig. 5 is an end view of the buckle and attached belt and illustrates the hinged belt retaining means in both closed and open positions, and

Fig. 6 is a view in front elevation of the buckle with the belt retaining means in open position.

Similar characters of reference are employed in said views, to indicate corresponding parts.

Referring now to the said drawing, the reference numeral 1 designates the free end portion

of a belt or strap having its other end portion 2 attached to the anchor post 3 of the novel buckle 4 of this invention. The buckle 4 is of substantially channel shape, having a vertical web or back portion 5 provided at its upper and lower edges with forwardly projecting flanges 6 and 7, respectively, the web 5 together with flanges 6 and 7 forming the body of the buckle. The flanges 6 and 7 cooperate with the web 5 in providing a channel for slidably receiving the belt end portion 1. The anchor post 3 interconnects the flanges 6 and 7 at one end of the buckle 4, there being a vertical slot or aperture 11 provided between post 3 and the web 5 to accommodate the looped belt end portion 2.

A stud 8 is secured as by riveting to the central portion of web 5 and projects forwardly for engaging in sockets or recesses 9 provided in the belt free end portion 1. The sockets 9 are spaced at intervals longitudinally of the belt free end portion and each of these sockets extends from the rear face of the belt forwardly partly through the belt toward the front face thereof and is shown as provided with a reinforcing ferrule 10.

The end of the buckle 4 that is remote from the post 3 is provided with a vertical belt retaining bar or member 12 which extends between and interconnects the forward edges of flanges 6 and 7. The bar 12 is fixed to the forward edge portions of flanges 6 and 7 and serves to confine the belt end portion 1 between the same and the web 5 when this belt end portion is in the buckle. A hinged belt retaining bar or member 13 is positioned at the other end of the buckle 4, i. e. in front of post 3 and has a hinge knuckle 14 at its upper end portion hingedly connected by a hinge pin 15 to hinge knuckles 16 provided on the upper forward portion of flange 6. The bar 13 is adapted to extend downwardly in abutting relation to the forward edges of flanges 6 and 7. The lower or free end portion of bar 13 is provided with a catch lip 17 for snapping over and engaging a depending catch projection 18 provided in the forward lower surface of flange 7.

With the catch lip 17 engaging the catch projection 18, as shown in Figs. 1, 2 and 3, the bar 13 cooperates with bar 12 in retaining the belt end portion 1 within the buckle channel so that the stud 8 projecting into one of the sockets 9 will serve to hold or lock the belt end portion 1 in fixed position with respect to the buckle. When it is desired to adjust the belt with respect to the buckle, i. e. to vary the effective length of the belt, it is merely necessary to pull the lower or free end of bar 13 forwardly, thereby causing

catch lip 17 to disengage catch projection 18, whereupon the bar 13 may be turned upwardly as shown in Figs. 4 and 6. The belt end portion 1 may now be readily pulled forwardly somewhat, 5 causing the same to disengage stud 8, whereupon the belt may be easily adjusted or moved longitudinally with respect to the buckle. During this adjustment of the belt, the fixed bar or member 12 serves to retain the belt end portion 1 within the buckle channel i. e. in assembled relation with respect to the buckle, so that after the effective length of the belt has been adjusted as desired, it is merely necessary to move the belt end portion 1 inwardly to cause stud 8 10 to engage in one of the sockets 9. The bar 13 is then turned downwardly and pressed inwardly so that catch lip 17 again snaps over catch projection 18, whereupon the belt end portion 1 is again locked in the buckle.

20 It will be apparent that the retaining bar 13 may be of various shapes or dimensions. For example, the same may be of ring or oval shape as for ornamental purposes and may even be of such width as to overlap the stud 8, thereby positively insuring the retention of the belt in place.

25 As many changes could be made in the above construction and many apparently widely different embodiments of this invention could be made without departing from the scope thereof, 30 as defined by the following claims, it is intended that all matter contained in the above description or shown in the accompanying drawing shall be interpreted as illustrative and not in a limiting sense.

35 I claim:—

1. A buckle of the character described for use with belts and the like, comprising a channel shaped body providing a receiving recess for the free end portion of a belt and having means at 40 one end thereof for attachably receiving the fixed end portion of the belt, a retaining bar fixed to the other end portion of said body in overlying relation to said recess for retaining the free end portion of the belt in assembled relation with the buckle, a stud projecting from said body within said recess, the height of said stud being less

than the thickness of the belt used with the buckle for cooperating with sockets in the rear surface of the belt, a second and similar retaining bar spaced from said first named retaining bar, said second retaining bar being hingedly connected to said buckle body and arranged to cooperate with said first retaining bar to retain the belt within said recess and in engagement with said stud, said second retaining bar being turnable away from said recess to enable the 10 disengagement of said belt from said stud as when varying the effective length of the belt, the unapertured portion of the belt extending between said retaining bars being exposed in use, thereby giving the buckle a highly attractive 15 appearance.

2. A buckle of the character described for use with belts and the like, comprising a channel shaped body providing a receiving recess for the free end portion of a belt and having means at 20 one end thereof for attachably receiving the fixed end portion of the belt, a relatively narrow retaining bar fixed to the other end portion of said body in directly overlying relation to said recess for retaining the free end portion of the belt in assembled relation with the buckle, a stud projecting from said body within said recess for cooperating with sockets provided in the rear surface of the belt, a second and similar retaining bar spaced substantially the full length of 30 the buckle from said first named retaining bar, said second retaining bar being hingedly connected to said buckle body at one side of said recess and having a catch lip at its free end, said body having a catch projection at the other side 35 of said recess for cooperating with said catch lip to cause said second retaining bar to cooperate with said first retaining bar to hold the belt within said recess and in engagement with said stud, the run of the belt between said retaining bars being exposed to view, said second retaining bar being turnable outwardly of said recess thereby enabling the disengagement of the belt from said stud.
